UNITED STATES PATENT OFFICE.

JAMES J. COOPER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,109,624.

Specification of Letters Patent:

Patented Sept. 1, 1914.

Application filed January 14, 1913. Serial No. 741,999.

To all whom it may concern:

Be it known that I, JAMES J. COOPER, a citizen of the United States, residing at St. Louis, Missouri, have invented a certain 5 new and useful Improvement in Railway-Car End Construction, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction. Fig. 2 15 is a vertical section taken on the line 2—2 of Fig. 1. Fig. 3 is a plan view of the car end.

My invention relates generally to railway car bodies, and more particularly to the 20 construction of the car body end wall.

In railway cars, and particularly those designed for freight service, the end portions of the car bodies, and particularly the end walls are subjected to severe stresses and 25 strains due to the sudden starting and stopping of the cars and consequent vibration, also by reason of the shifting of the load or contents of the cars while the latter are in transit, and by reason of shocks and blows 30 delivered to the end portion of the car while the same is in service.

I propose to construct a car end wall from sections of sheet metal, the same being provided with pressed ribs or corrugations, 35 so arranged as to stiffen and strengthen the plate to a maximum degree, and by virtue of such construction all stresses or strains imparted to the end wall or plate will be transmitted to the end sill and plates of the car 40 body frame.

The principal object of my invention is to construct the car end wall from a plurality of pieces of material, preferably sheet metal, each piece or section being reinforced and 45 stiffened by means of ribs or corrugations pressed in the metal, thus providing a comparatively simple, inexpensive construction which can be readily utilized with an ordinary car underframe and superstructure, 50 and which will be effective in resisting all stresses and strains resulting from shifting loads, ordinary service shocks and vibrations, or collisions.

A further object of my invention is to

construct a car end wall or plate in sections, 55 thereby making it possible to utilize comparatively small pieces of sheet metal in the formation of the completed end, which small pieces or sections can be more readily handled during the formation of the reinforcing ribs or corrugations than where a large single piece of material is utilized as the car end or plate.

To the above purposes my invention consists in certain novel features of construction and arrangement of parts hereinafter more fully described and claimed.

In the construction illustrated in Figs. 1 to 3 inclusive the car end wall is composed of two sections of sheet metal, the upper and lower and outer edges of which sections are bent at right angles to the plane occupied by the main body portions of the sections in order to form marginal flanges 2, whereby the end wall or plate may be readily attached to the car body frame. The inner or meeting edges of the two sections are bent outwardly, as designated by 3, to form coinciding flanges, and seated in these flanges are suitable fastening means such as rivets. By thus dividing the end wall on a central vertical line, and by forming flanges on the meeting edges of the sections, a centrally arranged, vertically disposed rib is provided for the end plate which materially 85 stiffens and strengthens the same.

Formed in the two sections of material of which the end plate is formed, and at points approximately midway between the top and bottom of said end plate, are horizontally 90 disposed ribs or corrugations 4 which start near the outer edges of the sections and gradually become deeper and wider toward the inner meeting edges of said sections. By such construction a centrally arranged, horizontally disposed rib or corrugation is formed in the end plate, which rib or corrugation intersects the vertically disposed strengthening and reinforcing rib or member comprising the coinciding flanges 3.

Formed in the sections of metal of which the end wall or plate is composed, and located above and below the horizontally disposed ribs or corrugations 4 are pairs of diagonally disposed ribs or corrugations 5 which gradually become deeper and wider toward the inner meeting edges of the sections, and the members of each correspond-

ing pair of these ribs or corrugations 5 unite, as designated by 6, immediately adjacent to the inner edge of the corresponding section. By virtue of such construction the upper and 5 lower portions of the end wall or plate, or those portions above and below the horizontally disposed reinforcing rib or corrugation, are stiffened and reinforced by the diagonally disposed ribs or corrugations which practically 10 intersect one another, the point of intersection being coincident with the vertically disposed rib or reinforcement formed by the outwardly turned flanges 3.

By my improved arrangement of ribs or 15 corrugations the entire end wall or plate is materially stiffened and strengthened, and when the same is combined with the under-frame and superstructure of a car body all ordinary stresses and strains imparted to the 20 end wall or plate will be effectively resisted.

The ribs or corrugations are formed in the sheet metal in any suitable manner, preferably by means of presses, and by forming said end wall or plate in sections, the latter 25 can be more readily handled by the workmen during the formation of the ribs or corrugations than where the end plate is formed in a single large section.

My improved construction effects a material saving in the initial cost of construction 30 of the car end and in the cost of repairs, and by the formation of the ribs or corrugations in the sections of sheet metal forming the end wall, the latter is materially reinforced 35 and strengthened against internally or externally applied stresses, and the impact of all blows which the end plate may receive in service are transmitted to the walls and plates forming a part of the car body frame.

40 It will be readily understood that minor changes in the size, form and construction of the various parts of my improved car end may be made and substituted for those herein shown and described without departing 45 from the spirit of my invention, the scope of which is set forth in the appended claims.

I claim:

50 1. A car end comprising two conversely identical sheet metal sections, each section having formed therein reinforcing ribs or corrugations.

55 2. A car end comprising two conversely identical sheet metal sections, each section having formed therein reinforcing ribs or corrugations, and the ribs or corrugations of said sections joining at the junction of the sections.

3. A car end comprising two conversely identical sections of sheet metal in which are pressed reinforcing ribs or corrugations diverging from the junction of the sections. 60

4. A car end composed of two sections of sheet metal provided with stiffening ribs or corrugations which coalesce at the junction of the sections, the said sections having connecting flanges extending 65 from the protuberant sides of the corrugations.

5. A car end made up of a plurality of joined sections of sheet metal in which are pressed stiffening corrugations which coalesce at the junction of the sections, the said sections having connecting flanges extending 70 from the protuberant sides of the corrugations.

6. A car end composed of bi-laterally 75 symmetrical sections of sheet metal, the meeting edges of which are flanged and attached to each other, and said sections having formed therein stiffening and reinforcing ribs or corrugations continuing to said 80 flanged edges.

7. A car end composed of separate sections of sheet metal joined together, said sections being provided with diagonally disposed 85 stiffening ribs or corrugations which intersect at the junction of the sections.

8. A car end comprising a plurality of sections of sheet metal secured together at their vertical edges and provided with a medially disposed horizontal stiffening corrugation and diagonally extending corrugations above and below said medial corrugation, said corrugations being continuous substantially from side to side of the 90 end structure. 95

9. A car end composed of a plurality of sheet metal sections having vertical edges flanged and joined to form vertical stiffening members, said sections being provided with stiffening corrugations diverging from 100 said flanged edges.

10. In a car end, a sheet metal panel provided with stiffening corrugations and having an attaching flange shaped to accommodate 105 said corrugations.

In testimony whereof I hereunto affix my signature in the presence of two witnesses, this eighth day of January, 1913.

JAMES J. COOPER.
